TWO-STROKE INTERNAL COMBUSTION
ENGINE

Walter Schenker, Winterthur, Switzerland

Application December 2, 1936, Serial No. 113,921
In Switzerland March 31, 1936

4 Claims. (Cl. 123—65)

The invention relates to two-stroke internal combustion engines, both single acting and double acting engines, wherein the exhaust and admission ports in the cylinder are opposite one another and are controlled by the piston and wherein the admission ports are so directed that the air streams of the outer ports mainly impinge upon one another in the cylinder half on the admission side and are for the major portion diverted beyond the middle of the cylinder by the air streams of the inner ports. The primary object of the invention is to so direct the air stream during the first portion of the admission period that it mainly rises upwardly in the cylinder half on the inlet side and thus produces a so-called arcuate scavenging. During the remaining portion of the admission period a pronounced inclined position is adapted to be imparted to the air-stream, that is to say its direction is to extend, starting from the admission ports, upwardly at an angle for example towards the corner which is formed by the cylinder head and the cylinder wall on the exhaust side, for the purpose of bringing the circulating movement of the preceding arcuate scavenging to rest or to convert it into a countermovement. According to the present invention this double result is obtained, without for example the necessity of applying the known means of deviation by additional air at higher pressure, in a simple manner by adjusting the air of the inner admission ports. This adjustment consists in a delay of the air passage or by throttling during the first portion of the admission period, whereby the deviating action of the middle streams on the remaining air is eliminated completely or for the major part and therefore the complete air stream is caused to rise upwardly in the cylinder half on the admission side. During the remaining portion of the admission period throttling, however, does not take place whereby the deviating action of the middle air stream comes into action to the full extent and imparts the necessary inclination to the air stream. The temporary flow in a straight line direction of the air stream and the succeeding inclination may be suitably selected. For example provision may be made for a gradual transition in the change of direction.

The admission ports may have a suitable usual inclination relatively to the cylinder axis. The upper limiting surface may for example be the same in connection with all the ports and have an inclination of 45°. The ports must, however, always be so shaped that when all the ports fully co-operate with one another the major portion

of the air reaches the upper part of the cylinder in the half thereof on the exhaust side or that even a still greater inclination is obtained.

As a rule it is desirable to particularly maintain the direction of the air stream during the first portion of the admission period. This result may be obtained when the cross-sectional area, of the outer ports is made as large as possible, for example by making these ports at least of the same height as the exhaust ports. Or the shape of the ports may be such and the air streams therefrom simultaneously adjusted in such a manner that the kinetic energy of the air masses flowing from the ports differs decreasingly from the outer to the inner ports. 15

For carrying out the method of adjustment above described it would suffice to connect the charging air container by means of valves or similarly acting cut-off members and by means of a common air chamber with the ports. This, however, would necessitate the provision of the adjusting devices directly at the ports. When, however, the air chamber is divided in an axial direction into a number of chambers, by partitions, this enables the adjusting members to be 20 located at suitable points or the cut-off members themselves may serve for the adjustment. The sub-division of the air chambers, as a rule, is to be so selected that there is a common air chamber for the middle ports. However, it is also 25 possible to provide two or more middle air chambers. The partitions need not be gastight. Partitions which are fitted into position without any separate packing at the joints would, for example, provide a sufficient limitation. 30

Various examples of construction are shown diagrammatically in the accompanying drawing, wherein

Figs. 1, 2 and 3 show a first example of construction in which five air chambers are provided, Fig. 1 being a vertical section, Fig. 2 being a horizontal section on line 2—2 of Fig. 1, and Fig. 3 being a section on the line 3—3 of Fig. 1. 40

Fig. 4 shows a vertical section of an air chamber with two valves. 45

Figs. 5 and 6 show a construction with three air chambers; and Fig. 7 shows the valves and air chambers in cross-section on the line 7—7 of Fig. 6.

Fig. 8 shows an air chamber with two valves 50 and an additional chamber with two control members.

Fig. 9 shows an air chamber controlled by a rotary valve.

A is the cylinder, B the charging air container, 55

P the piston. C indicates the exhaust ports and S is the exhaust pipe. In Figs. 1 and 2 the three inner admission ports D extend upwardly to a higher level than the exhaust ports. Of the 5 outer admission ports E₁ and E₂ the latter extend to the level of the exhaust ports, whilst the former are lower. F, F₁ and F₂ indicate the five air chambers, H, H₁ and H₂ the corresponding valves which control the connection with the charging 10 air container B. These valves may be automatic or, as shown in Fig. 1, may be actuated by rotating actuating cams or otherwise. The valves H₂ are of larger dimensions than the valves H₁. It is also possible to provide two or more valves 15 for each air chamber. The scavenging and charging operation takes place in the following manner. During the downward movement of the piston P the ports D are opened first, later the exhaust ports C and at the same time the 20 admission ports E₂. A return flow of the exhaust gases into the charging air container B is prevented in that the valves H, H₁ and H₂ are kept closed until the pressure of the exhaust gases has sunk below the scavenging or charging pressure. 25 This will approximately be the case when the lower admission ports E₁ commence to open. The valves H₁ and H₂ are now opened, and at the same time or somewhat later there is also opened the valve H so that during the first portion of 30 the admission period of the ports E₁ and E₂ no air or only a small amount of air flows from the ports D. The total air stream therefore rises in the cylinder half on the admission side, turns, when reaching the cylinder head, towards the 35 exhaust side and finally flows downwardly towards the exhaust ports driving the exhaust gases in front of it.

During the second portion of the admission period, which as a rule constitutes about half of 40 the entire admission period, the throttling of the middle streams is reduced to the minimum amount obtainable. The strength of the middle streams is thus increased and consequently also their deviating action and the complete charging 45 stream is inclined more and more towards the exhaust side and the circulating movement of the air, of which the direction in this case is in an anti-clockwise direction, has a braking action applied thereto.

Figs. 5, 6 and 7 show an arrangement with three 50 air chambers, the valves and air chambers being shown in cross-section in Fig. 7 on the plane 7—7 of Fig. 6. The air chamber F is provided with an automatic valve H and each of the chambers F₁ is provided with two valves H₁. Between the middle chamber F and the charging air container B there is provided a separate chamber R which, on the one hand is connected through an automatic valve M to the charging air container 55 and on the other hand by a valve H to the chamber F. Since the pressure in the cylinder is lower than in the container B, the valve H first opens. In consequence, the pressure in the chamber R falls by a slight amount, whereby the valve M 60 will open through the over-pressure of the container B. Valve M therefore opens later than valve H. This delay can be further magnified, i. e. the commencement of the stroke of the valve M can be temporarily delayed, when air from 65 the charging air container is supplied to the chamber R through the air passages T, so that the negative pressure increases more slowly. These air passages may be provided at suitable 70 points of the chamber R. For example an air gap may be provided on the adjusting member M

in that the valve plate is made smaller in diameter than the corresponding through-flow passage. The member is thus without a seat and its position of rest must be limited by the force of a spring. The duration of lifting of the valve 5 M, i. e. the duration of throttling the middle air streams can be suitably adjusted by a predetermined selection of the member, preferably with the co-operation of spring forces by any generally known means. If, for instance, the weight of 10 the valve M is greater, the valve will open more slowly, corresponding to its greater mass. The same action would occur if the valve springs were strengthened (or thickened).

In the examples described there may be used 15 instead of a single valve H for the air chamber F also two or more thereof (see Fig. 8), whilst it is possible to provide a plurality of adjusting members M. As closure members for the air chambers it is also possible to use instead of the 20 valves described other control devices, such as for example rotary valves (see Fig. 9). The invention also includes cases in which a portion of the air from the outer ports is not subjected to the deviating action by the middle air streams. 25

What I wish to claim is:—

1. In a two-stroke internal combustion engine, the combination comprising a cylinder, said cylinder having exhaust and admission ports therein, said exhaust and admission ports being located 30 opposite one another, the admission ports being divided into two series, the first series being located on the admission side of said cylinder and the second series being located at the middle of the cylinder between the first series and the exhaust ports whereby air streams entering the second series of admission ports are directed to flow mainly in a longitudinal direction on the inlet side of the cylinder to the cylinder cover and where said air streams are deviated temporarily by air streams from the first series of admission ports to the exhaust side of the cylinder, a working piston in said cylinder, said piston during its movement being adapted to control said exhaust and admission ports, a charging air 45 container, a second chamber located between said charging air container and said admission ports, and communicating with said charging air container and said admission ports, valve means controlling communication between the 50 second chamber and the charging air container, and partitions located in said second chamber, said partitions dividing said second chamber into several compartments, one of said compartments communicating with the first series of admission 55 ports and the other compartments communicating with the second series of admission ports.

2. In a two-stroke internal combustion engine, the combination comprising a cylinder, said cylinder having exhaust and admission ports therein, said exhaust and admission ports being located opposite one another, the admission ports being divided into two series, the first series being located on the admission side of said cylinder and the second series being located at the middle of 60 the cylinder between the first series and the exhaust ports whereby air streams entering the second series of admission ports are directed to flow mainly in a longitudinal direction on the inlet side of the cylinder to the cylinder cover 65 and where said air streams are deviated temporarily by air streams from the first series of admission ports to the exhaust side of the cylinder, a working piston in said cylinder, said piston during its movement being adapted to con- 70

trol said exhaust and admission ports, a charging air container, two air chambers associated with the second series of the admission ports and communicating with the air container by valves, a 5 third chamber associated with the first series of admission ports, an additional chamber with automatic valves therein, communicating said additional chamber with the third chamber and valves communicating the additional chamber 10 with the air container, these latter valves acting as control members.

3. In a two-stroke internal combustion engine, the combination comprising a cylinder, said cylinder having exhaust and admission ports therein, 15 said exhaust and admission ports being located opposite one another, the admission ports being divided into two series, the first series being located on the admission side of said cylinder and the second series being located at the middle of 20 the cylinder between the first series and the exhaust ports whereby air-streams entering the second series of admission ports are directed to flow mainly in a longitudinal direction on the inlet side of the cylinder to the cylinder cover 25 and where said air-streams are deviated temporarily by air-streams from the first series of admission ports to the exhaust side of the cylinder, a working piston in said cylinder, said piston during its movement being adapted to control 30 said exhaust and admission ports, a charging air container, a chamber located between said charging air container and said admission ports, and communicating with said charging air container and said admission ports, control members controlling communication between the chamber and 35 the air container, partitions located in said cham-

ber, said partitions dividing said chamber into a plurality of compartments, and throttling means controlling the air of the first series of admission ports.

4. In a two-stroke internal combustion engine, 5 the combination comprising a cylinder, said cylinder having exhaust and admission ports therein, said exhaust and admission ports being located opposite one another, the admission ports being divided into two series, the first series being located on the admission side of said cylinder and the second series being located at the middle of the cylinder between the first series and the exhaust ports whereby air-streams entering the second series of admission ports are directed to 10 flow mainly in a longitudinal direction on the inlet side of the cylinder to the cylinder cover and where said air-streams are deviated temporarily by air-streams from the first series of admission ports to the exhaust side of the cylinder, 15 a working piston in said cylinder, said piston during its movement being adapted to control said exhaust and admission ports, a charging air container, two air chambers associated with the second series of the admission ports and communicating with the air container by valves, a third chamber associated with the first series of admission ports, an additional chamber, automatic valves therein, for effecting communication between said additional chamber and the third 20 chamber, and valves for effecting communication between the additional chamber and the air container, these latter valves acting as control members.
